Primary Examiner — Robin V Webster*Assistant Examiner* — J. Thorn, Sr.(74) *Attorney, Agent, or Firm* — Quickpatents, LLC;
Kevin Prince(57) **CLAIM**

We claim the ornamental design for a bra with breast milk collection, as shown and described.

DESCRIPTION

FIG. 1 is a front perspective view of a bra with breast milk collection, showing our new design in a fastened configuration;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear perspective view thereof, illustrated in an unfastened configuration.

The broken lines in the drawings depict stitching in the fabric.
